John Ashcroft

United States Patent Office.

JOHN ASHCROFT, OF NEW YORK, N. Y.

Letters Patent No. 80,700, dated August 4, 1868.

IMPROVEMENT IN LOW-WATER DETECTORS FOR BOILERS.

The Schedule referred to in these Letters Patent and making part of the same.

TO ALL WHOM IT MAY CONCERN:

Be it known that I, JOHN ASHCROFT, of the city, county, and State of New York, have invented a new and useful Combination of Low-Water Detector and High-Pressure Steam-Alarm for Steam-Boilers; and do hereby declare that the following is a full, clear, and exact description thereof, reference being had to the accompanying drawings, making part of this specification, of which—

Figure 1 is a side elevation, and

Figure 2 a vertical section.

This invention relates to a novel device for giving an alarm when the water in a steam-boiler is below the proper level, as well as for giving an alarm when the steam in said boiler is above the desired pressure, and consists of two separate and distinct tubes placed at some distance apart, said tubes extending down into the boiler and above the same, the one designed for a low-water detector, having perforations for the admission of steam within the boiler, and a fusible plug in said tube above the boiler. The other tube, designed for high-pressure steam-alarm, also extends down into the boiler and above the same, and has steam-inlet openings within the boiler. The part of said tube which extends upward outside the boiler contains an adjustable weighted valve and a steam-whistle, both tubes being united within and above the boiler, one steam-whistle being used for both.

In the drawings—

A denotes a portion of a steam-boiler to which my invention is attached.

B is the low-water indicator, having perforations C C for admission of steam when the water exposes the perforations by descending below the proper level.

D is the fusible plug in said tube, and

E the steam-escapes.

F is the high-pressure steam-alarm tube, having steam-inlets G G within the boiler, while outside the boiler the said tube contains an adjustable weighted valve, H, and steam-whistle, I, enclosed in a case, K.

Between the low-water alarm-tube B and the high steam-pressure tube F are connections, L M N, the latter being a steam-connection, and having a valve, O, for admitting steam to the whistle when said plug is dissolved by the steam, (see fig. 2.)

The operation of my invention is as follows:

As the water in the boiler descends below the perforations C C in the low-water tube B, the steam enters said perforations, and will dissolve the fusible plug D, escaping through the open end E of the pipe B, and through the connection e N, lifting the valve O from its seat, and reaching the whistle, will give the alarm for low water in the boiler, while the high steam will enter the tube F, raise the weighted valve H, and reaching the steam-whistle I, will give the alarm for steam of undue pressure.

Having described my invention, what I claim as new, and desire to secure by Letters Patent, is—

1. The construction, arrangement, and combination of the low-water detector-tube B and fusible plug D, with the steam-alarm tube F, weighted valve H, and steam-whistle I, substantially as shown and described.

2. I also claim the steam-connection pipe N and valve O, in combination with the fusible plug D and steam-whistle I, substantially as herein shown, described, and set forth.

In testimony whereof, I have hereunto set my signature, this 29th day of June, 1868.

JOHN ASHCROFT.
